NAIL CLIPPER

William L. Berry, Maywood, Ill., assignor to H. Fishlove and Co., Chicago, Ill., a corporation of Illinois

Filed Feb. 28, 1967, Ser. No. 5,999

Term of patent 14 years

(Cl. D86—10)

I claim:

The ornamental design for a nail clipper, as shown.
